UNITED STATES PATENT OFFICE.

SAMUEL I. BERGER, OF NEWARK, NEW JERSEY.

DESIGN FOR A STATUETTE.

Application filed May 11, 1925. Serial No. 13,407. Term of patent 3½ years.

To all whom it may concern:

Be it known that I, SAMUEL I. BERGER, a citizen of the United States, and residing at Hotel Riviera, Newark, in the county of Essex and State of New Jersey, have invented a new, original, and ornamental Design for Statuette, of which the following is a specification, reference being had to the accompanying drawings, forming part hereof.

The figure shows a front elevation of the statuette embodying my new design.

I claim:

The ornamental design for a statuette as shown.

SAMUEL I. BERGER.
